H. M. LLOYD

READY BUILT LAMP POST

Filed Dec. 11, 1926

Inventor
Harold M. Lloyd.

Lyon & Lyon Attorneys

UNITED STATES PATENT OFFICE.

HAROLD M. LLOYD, OF LOS ANGELES, CALIFORNIA.

READY-BUILT LAMP-POST.

Application filed December 11, 1926. Serial No. 154,073.

This invention relates to lamp posts such as used for supporting street lamps. The usual construction for lamp posts includes a base, a column, and a cap, the cap being surrounded by the bracket which carries the lamp or lamps. The foundation bolts are within the periphery of the base and in erecting the post the base must be put in position and secured to the foundation, and on this base the column and cap are secured. This necessitates the transportation of the separate parts to the point where the post is to be set up, and also requires special operations in erecting the post.

The general object of this invention is to provide a ready-built post, in which the base, the column, and the cap are permanently secured together and to a base plate which seats upon the foundation; and to construct the post in such a way that the complete post can be readily set up on the foundation.

Further objects of the invention will appear hereinafter.

The invention consists of the novel parts and combination of parts to be described hereinafter, all of which contribute to produce an efficient ready-built lamp post.

A preferred embodiment of the invention is described in the following specification, while the broad scope of the invention is pointed out in the appended claims.

The accompanying drawings illustrate the invention:

Figure 1 is a side elevation and partial section through a lamp-post embodying my invention, and also showing the foundation in cross-section.

Fig. 2 is a horizontal section on an enlarged scale taken through the base of the post upon the line 2—2 of Fig. 1.

Fig. 3 is a vertical section taken on the line 3—3 of Fig. 2 and broken away.

Fig. 4 is a horizontal cross-section taken on the line 4—4 of Fig. 1 and particularly illustrating the arrangement of the tie bolts which attach the parts together.

In practicing the invention I provided a hollow base 1 which is open at its lower end, and provided at its upper end with a transverse head or flange 2 at which point the base is formed with a neck 3 of reduced diameter. At the base of the neck a circumferential shoulder 4 is formed. The neck 3 is received in the lower end of a tubular column 5, the

lower end of the column being seated against the shoulder 4.

On the upper end of the column 5 a cap 6 is received, said cap having a reduced neck 7 at its lower end which is received in the upper end of the column. The lower end of the cap has an annular shoulder 8 which seats against the end of the column.

The cap 6 is hollow and provided at its upper end with a transverse head or ring 9.

The lower end of the base is received on a base plate or base ring 10. The base may be of octagonal form and the base ring may be provided with a shoulder 11 which extends around the base ring to fit the octagonal shape of the base. In other words, the upper side of the base ring has a short octagonal "neck" which projects up into the base at its lower end. By reason of its octagonal or angular form the base plate of course will keep the base from shifting or rotating around its own axis.

The parts referred to above are all secured together at the factory. In order to do this I prefer to provide upper tie rods 12 which extend downwardly from the ring or head 9 of the cap, passing down through the column 5 and through the head or ring 2 at the upper end of the base. There are preferably three of these tie rods, and their threaded ends are provided with nuts 13 for tightening them up. These tie rods securely connect the base, the column, and the cap together.

The base ring 10 is secured to the base by means of tie rods 14, preferably three in number, the upper ends of which are attached to the head or ring 2, and the lower ends of which pass downwardly through the base ring; the lower portions of the tie rods 14 are off-set outwardly on account of the expanded width of the lower end of the base. The threaded ends of the tie rods 14 are provided with nuts 15 for tightening these rods.

The base ring 10 is preferably of ring form in order to provide a central opening 16 through it which enables it to receive the upper ends of elbows 17 of conduits 18 which bring the electric wires 19 into the base. If desired, the base 1 may be provided with a door 20 to give access to these wires.

If desired, the inner face of the base may be provided with a flange 21 which seats upon the inner and raised portion of the base ring.

The bolts which secure the lamp post on

its foundation or pier 22 are all disposed outside of the periphery of the base 1. These foundation bolts 23 may be four in number, and are anchored in the concrete of the foundation. Their upper ends extend through openings 24 formed in flanges 25 at the corners of the base plate; that is to say, the corners of the base plate project outwardly from the side of the base and operate as flanges 10 upon which the nuts 26 seat in securing the lamp post in position.

I claim:

1. In a ready-built lamp-post, the combination of a base, a column supported on the base, a cap on the upper end of the column, tie-bolts extending through the column and connecting the base and the cap to the ends of the column, a base-plate, tie-bolts extending down through the interior of the base 20 and securing the same to the base-plate, said base-plate having external flanges projecting outwardly beyond the side wall of the base with openings to receive foundation bolts.

2. In a ready-built lamp-post, the combination of a hollow base open at its lower end and having a head at its upper end, a column seated on the upper end of the base, a hollow cap seating on the upper end of the column having a head at its upper end, tie-

bolts extending down through the cap and the column and connecting together the column, the base and the cap, a base-plate operating as a seat for the lower end of the base, tie-bolts extending through the head of the base and through the base-plate for attaching the base-plate to the base, said base having external flanges projecting outwardly beyond the side wall of the base with openings to receive foundation bolts.

3. In a ready-built lamp-post, the combination of a hollow cap having a head at its upper end, a hollow base having a head at its upper end, a tubular column between the cap and the base, tie-bolts extending through the cap and the column and attaching the same to the upper end of the base, a base-plate in the form of a ring with a central opening to permit electric cords to pass upwardly into the base, tie-bolts attached to the head at the upper end of the base and offset outwardly at their lower portions, with their ends secured in the base-ring, said base-ring having external flanges projecting outwardly beyond the side wall of the base with openings to receive foundation bolts.

Signed at Los Angeles this 1st day of Dec., 1926.

HAROLD M. LLOYD.
